UNITED STATES PATENT OFFICE.

JOHN STANLEY MUIR, OF DETROIT, MICHIGAN.

MECHANICAL SIGNAL-HORN.

1,188,673.

Specification of Letters Patent. Patented June 27, 1916.

Application filed March 16, 1915. Serial No. 14,627.

To all whom it may concern:

Be it known that I, JOHN STANLEY MUIR, a citizen of the United States, residing at Detroit, in the county of Wayne and State of Michigan, have invented new and useful Improvements in Mechanical Signal-Horns, of which the following is a specification.

This invention relates to a mechanical signal horn for automobiles, motor boats, and other similar vehicles, the object of the invention being to provide a horn which, while simple of construction and inexpensive of production, will produce a maximum volume of sound.

15 A further object of the invention is to provide a signal horn which is adapted to be rotated for operation by a moving part of the motive plant of the vehicle, and which may be thrown into and out of action at will.

20 A still further object of the invention is to provide a novel construction of signal horn, embodying fixed and rotating parts, including sound producing devices, adapted to be operated by the rotation of the rotary part, together with means whereby the device as a whole may be adjusted into and out of engagement with the moving part of the motor mechanism, to render the horn operative or inoperative at will.

25 The invention consists of the features of construction, combination and arrangement of parts herein fully described and claimed, reference being had to the accompanying drawings in which:—

30 Figure 1 is a perspective view of a portion of an automobile, showing one mode of application of the invention. Fig. 2 is a plan view of the horn, on an enlarged scale, parts of the horn appearing in section. Fig. 3 is a face view of the horn *per se*. Fig. 4 is a vertical section on the line 4—4 of Fig. 2. Figs. 5 and 6 are detail views of parts of the sounding mechanism.

35 In carrying my invention into practice, I provide a horn comprising a casing 1 consisting of front and rear sections 2 and 3, formed of sheet metal or other suitable material. The two sections of the casing have portions 4 and 5 which relatively converge 40 in an outward direction and form a sounding chamber 6 in which is disposed a disk or diaphragm 7.

45 The disk or diaphragm 7 is composed of a thin circular piece of steel or other similar material, capable of vibration to produce a maximum volume of sound. The marginal

portion of this diaphragm extends beyond the chamber 6 and is clamped between suitable gaskets 8 disposed between the same and angular clamping members 9 and 10, which are integral with the converging portions 4 and 5 of the casing sections, the parts referred to being firmly united by rivets or other suitable fastening devices 11.

50 The casing and parts carried thereby are mounted for rotary motion as hereinafter described, and the clamping members 9 and 10 are extended beyond the diaphragm to provide a channeled rim 12 receiving a ring 13 which is securely clamped therein. This ring may be made of wood or other suitable material, and provides a friction wheel or surface which is adapted for engagement with a moving part of the engine or power plant of the vehicle, whereby the rotary portion of the device may be rotated.

55 The casing section 2 is provided with a sound outlet 14, while the casing section 3 is provided with a tubular portion or hub 15 which is secured to and mounted upon a wheel or rotary head 16 provided with a bearing sleeve 17 and an annular toothed surface 18. This toothed wheel is mounted to revolve upon a shaft or axle 19 carried by a hanger arm or bracket 20, to which it is secured by a set screw or other suitable fastening means 21.

60 The toothed wheel constitutes one of the elements of the sounding mechanism, which consists, in addition to the diaphragm and said toothed wheel, of a gravity dog or pawl 22 adapted to engage and coöperate with the teeth of said wheel, which dog or pawl is connected with a vibrating hammer or striker 23, pivotally mounted upon a bifurcated arm 24, formed upon and disposed at an angle to the outer end of the shaft or axle 19.

65 The hanger or bracket arm 20 is rigidly connected with a shaft or axle 24', journaled in one or more supporting bracket members 25, which may be mounted at any suitable point upon the vehicle, and connected with the arm 20 or shaft 24' is an operating member 26, which may be in the form of a pin, lever or other suitable form of device, whereby the shaft 24' and arm 20 may be rocked by hand or foot power to swing the horn in an arcuate path, to throw it into and out of action. Suitable means, as a spring 27, may be provided to support the hanger arm and horn in normally retracted posi-

tion, and which is adapted to permit the same to be adjusted for the purpose of throwing the horn into operative position.

In practice, the rock shaft 24' may be mounted by the bracket or brackets 25 upon the casing of the automobile or motor boat, or upon some other suitable part of the vehicle, and the device may be so arranged that the friction surface 13 may be thrown into and out of engagement with either the fly wheel of the engine or a belt driving a fan or other part, so that the rotary portion of the device may be set into action for the purpose of operating the sounding mechanism.

It will be evident from the foregoing description that the casing or body of the horn will, when the horn is thrown into action, be revolved with the wheel 16 upon the axle 19, and that as it revolves the toothed surface of the wheel causes the weighted pawl or dog 22 to ride in and out over the teeth of the wheels and in so doing to vibrate or swing the hammer 23 rapidly back and forth, the degree of rapidity depending upon the speed of rotation of the horn. The hammer when thus vibrated strikes the steel diaphragm 7 and thus produces the desired sound or signal, which will be of ample volume at low speed rotation and will increase in volume and intensity as the speed of rotation increases. It will be understood of course, that the surface 13 of the rotary body is normally maintained out of contact with the part of the power plant with which it is thrown into engagement for operation, and that by tilting the device on the shaft 24 as an axis the surface 13 may be thrown into and out of engagement with the moving operating element. As shown in Fig. 1, the moving operating element may be a belt 28 which transmits motion from the motor to a cooling fan, and the operating lever 26 may extend through the dashboard of the vehicle, if an automobile, so as to be conveniently operated by the driver or chauffeur. The horn may thus be arranged to be inclosed within the hood or motor casing of the vehicle, rendering it unnecessary to use expensive materials in its construction, since owing to the fact that it is concealed ornamental quality is not essential. The device may, however, be arranged to operate interiorly or exteriorly of the hood and, owing to its simplicity of construction, may be manufactured, even in an ornamental way, at a comparatively low cost, while it is adapted to produce as high a degree of volume as desired.

I claim:

1. A mechanical horn comprising relatively stationary and rotary members, a diaphragm upon the rotary member, a vi-

brating hammer upon the stationary member arranged to strike said diaphragm, and means upon the rotary member for vibrating said hammer. 65

2. A mechanical horn comprising a stationary member, a rotary member, a vibratory diaphragm carried by the rotary member, a vibratory hammer supported by the stationary member, and means operated by the rotary member for vibrating said hammer. 70

3. A mechanical horn comprising a stationary member, a rotary member, a vibratory diaphragm carried by the rotary member, an axle pin carried by the stationary member, a vibratory hammer carried by said pin, a dog carried by the pin, and a toothed surface on the rotary member for communicating vibratory motion to the dog. 75 80

4. A mechanical horn comprising a stationary member forming an axle, a rotary member mounted to turn thereon, a diaphragm carried by said rotary member, a toothed surface on the rotary member, and a vibratory device pivotally supported on the stationary member and adapted to be vibrated by said toothed surface for engagement with the diaphragm. 85 90

5. A mechanical horn comprising a stationary member forming an axle, a horn body revolvably mounted thereon, a diaphragm carried by the horn body, a surface upon the horn body whereby rotary motion 95 from a source of power may be communicated thereto, a vibratory diaphragm upon the horn body, a hammer upon the stationary member for contact with said diaphragm, and means upon the horn body for vibrating said hammer. 100

6. A mechanical horn comprising a stationary member, a rotary member, a vibratory diaphragm carried by the rotary member, a toothed surface upon the rotary member, a movable hammer supported by the stationary member, and a member operated by said toothed surface for transmitting vibratory motion to said hammer. 105

7. A mechanical horn comprising a rotary member, a toothed ring thereon, said rotary member being provided with a friction surface, a diaphragm carried by the said rotary member, a stationary member, a dog or pawl upon the stationary member 110 and adapted to be vibrated by the toothed ring on the rotary member, and a vibrating hammer operated by said dog. 115

In testimony whereof I affix my signature in presence of two witnesses.

JOHN STANLEY MUIR.
